Primary Examiner — Martie K Holtje(74) *Attorney, Agent, or Firm* — Marshall, Gerstein & Borun LLP(57) **CLAIM**

The ornamental design for a flying toy, as shown and described.

DESCRIPTION

FIG. 1 is a front, right-side, and top isometric view of a flying toy showing the new design.

FIG. 2 is a front elevation view of the flying toy.

FIG. 3 is a rear elevation view of the flying toy.

FIG. 4 is a left-side elevation view of the flying toy.

FIG. 5 is a right-side elevation view of the flying toy.

FIG. 6 is a top plan view of the flying toy; and,

FIG. 7 is a bottom plan view of the flying toy.

The structural elements depicted by broken lines have been shown for the purpose of illustrating portions of the flying toy that form no part of the claimed design.
